UNITED STATES PATENT OFFICE.

HARRISON E. KOZER, OF WAYNESBURG, PENNSYLVANIA.

METALLIC ROOFING.

SPECIFICATION forming part of Letters Patent No. 269,297, dated December 19, 1882.

Application filed October 13, 1882. (No model.)

To all whom it may concern:

Be it known that I, HARRISON E. KOZER, a citizen of the United States, residing at Waynesburg, in the county of Greene and State of Pennsylvania, have invented certain new and useful Improvements in Metallic Roofing, of which the following is a specification, reference being had therein to the accompanying drawings.

10 My invention relates to metal roofing; and it consists in certain features hereinafter described, and specifically set forth in the claims.

Figure 1 is a perspective of a portion of a roof constructed in accordance with my invention. Fig. 2 is a section on the line *x x*; Fig. 3, a section on the line *y y*, and Fig. 4 an enlarged perspective. Fig. 5 illustrates a valley and gutter, and Fig. 6 a section of a standing seam.

20 Like letters refer to like parts in all the figures.

A represents the usual sheets of tin or other suitable roofing material, which are united by transverse seams *a* and by longitudinal standing seams *b*, which are preferably double, as shown at Fig. 2, and at the upper end these seams are turned down, in order to be securely covered by a ridge-piece of any desired form.

25 B represents a gutter, which, at the eave-line *b' b'*, is merged integrally into the main portion of the roof near said line, and is finally joined to said main portion of the roof by a double seam, C, which is flat between the longitudinal standing seams *b*. In this construction the gutter is formed of a series of sheets joined to each other by any suitable means. It may be either a flat lap, soldered seam, or a single or double flat folded seam, and said series is then shaped longitudinally to form

30 the gutter proper, B, and a plain water-shedding portion, B', which is without seam longitudinally; and an edge of this portion B' is adapted to be united to the main roof by a double folded seam, whereby no solder is required to render the connection of the gutter and roof water-tight.

35 It is apparent that the severest tests which metal roofs of ordinary construction are required to withstand are occasioned by the contraction and expansion of the material in consequence of the variation in temperature to which they are exposed and the wedging action

of freezing water in the joints. It is also found in practice that even tightly-soldered joints are frequently broken by these and other causes, 55 and that the most desirable joint is that which allows a degree of independent movement on the part of the sheets united to each other, and yet which maintains such a union between them as to prevent the entrance of water. 60

By uniting the gutter to the roof proper by a double joint and by the retention of the usual standing longitudinal seams, and providing a smooth, unobstructed water-shedding portion immediately at the eave-line, I produce a roof 65 which is adapted to successfully withstand the severest tests. It is evident that the same features may be applied to gutters which project beyond the eaves, or which are included within the same and to the valleys of roofs in 70 general. I therefore illustrate in Fig. 5 a portion of a roof of that class wherein a valley, D, is connected with gutters B, which are joined in a corner, as frequently occurs where wings join the main building. In this instance the 75 standing seams *b² b²*, which extend from ridge to gutter, and the longitudinal seams *b b*, are merged into each other by flattening the latter and folding the flattened ends thereof along with the edges of the roof which are folded to 80 form the seams, and, as clearly shown, the flattened portions of the seams *b* serve as outlets for or permit the free passage of the water from the divisions of the roof formed by the standing seams and into the gutters below, 85 and as said outlets occur at the lowest points in all of said divisions it is impossible for any material quantity of water to lodge near any of the joints to injure the same by rust or corrosion or by freezing. 90

The valley D may be joined to the gutters by a soldered joint, d, or (if desired) a double folded and flattened seam may be formed, as shown in the other intersecting seams of the roof. In practice it is not essential that the 95 transverse standing seams should be flattened their entire width or length, the only requisite being an outlet, and this can be formed at the center only, if desired, and such location and limitation of said flattened portion or outlet is 100 perhaps preferable, as it permits free access beneath said seams for the purpose of painting the exposed under surfaces thereof.

It is apparent that instead of twice folding

one ply of the seam and thrice folding the other
ply, as shown in Fig. 2, which also includes
the usual securing-strips, *e*, (shown in dotted
lines, Fig. 1,) the plies forming the seam may
5 each be twice folded, as seen in Fig. 6. In
fact, any usual standing seam may be united or
joined to an intersecting seam by flattening the
same before joining the flattened plies thereof
with those forming the adjacent seam, and
10 therefore I am enabled to apply my improve-
ments to roofs as at present constructed, as
in repairing and in supplying new gutters and
valleys a transverse seam, as *C*, and longitudi-
nal seams *b*², bounding the valleys, are formed
15 of the old material and the new joined thereto,
as shown. By my improvements a seamless
water-shed at the gutter-line and expandible
unsoldered water-tight seams are secured.

Having described my invention, what I
20 claim as new, and desire to secure by Letters
Patent, is—

1. In a roof, the combination of the roof-cover-
ing composed of the sheets *A*, united by
transverse seams *a* and standing double seams
b, flattened at each end, and the gutter *B* *B'*, 25
joined to said roof-covering by a double seam,
C, flattened between the said longitudinal
standing seams, substantially as shown and de-
scribed.

2. In a roof, the combination of the gutter *B* 30
and water-shed *B'*, formed in one piece, and
the sheets *A*, formed into a series of standing
seams flattened and united to the water-shed
by a double folded flattened unsoldered seam,
substantially as shown and described. 35

In testimony whereof I affix my signature in
presence of two witnesses.

HARRISON E. KOZER.
